UNITED STATES PATENT OFFICE.

WALTER S. BROWER, OF ALBANY, NEW YORK.

JEWELER'S DRILLING-MACHINE.

SPECIFICATION forming part of Letters Patent No. 269,174, dated December 19, 1882.

Application filed December 3, 1881. (No model.)

To all whom it may concern:

Be it known that I, WALTER S. BROWER, a citizen of the United States, and a resident of the city and county of Albany, and State of New York, have invented certain Improvements in Bench Drilling-Machines for Jewelers, Pearl-Setters, and Others, of which the following is a specification.

My invention relates to an improved bench drilling-machine for jewelers' use in which a bracket supporting the operating mechanism of the machine is provided with a clamping-jaw and a clamping-screw for holding the machine in firm attachment with the work-table; and the operating mechanism is made to consist of a drill-shaft provided with a bevel-pinion and a bevel drive gear-wheel provided with a crank-handle, and a drill-table, which is supported from the breast of the bracket and adapted to be moved vertically in either direction or be wholly removed.

The object of my invention is to provide a light and convenient drilling-machine, which will be readily attached to a bench or table, for use of jewelers, pearl-setters, and others requiring accurate work, and will enable the operator to have full control over the work being done, both in holding the metal being operated with and guiding and controlling the movements of the drill and the table holding the work while being drilled, so that the drilling will be done at the exact points in the metal required and to the depth designed by the operator revolving the driving mechanism of the drill with one hand, while he with the other hand holds the work to the table and elevates or lowers both together, as may be required. I attain this object by means of the devices constructed and arranged as illustrated in the accompanying drawings, in which similar letters of reference indicate like parts throughout the several views.

In the drawings, Figure 1 represents a side elevation of my improved drilling-machine. Fig. 2 is a front view of the breast of the drill bracket-frame and table. Fig. 3 is a horizontal view taken at line No. 1 in Fig. 1. Fig. 4 is a front view of the breast of the drill-bracket-frame and table, illustrating a modification of devices for holding and guiding the table; and Fig. 5 is a horizontal view of the same.

A represents the drill bracket-frame, made of metal, with substantially the form shown. Made with the upper portion of said bracket-frame are bearings *a* and *b*, in which the vertical drill-spindle *B* is supported and revolved. Secured in the upper end of bracket *A*, above bearing *a*, is the spindle *c*, on which is mounted the bevel-gear *C*, provided with crank-handle *D* for revolving said gear-wheel. Secured to *B* is the bevel-pinion *E*, which is actuated by bevel-gear *C*. 55

Made with the rear side of bracket *A* is the stationary clamping-jaw *d*, and at a distance of two inches (more or less) below said clamping-jaw is ear *e*, which ear is pierced vertically and provided with a screw-thread, in which works the clamping-screw *f*, provided on its upper end with a loose washer, *g*. By means of said clamping-jaw and clamping-screw the drill bracket-frame and its attached gear and drill spindle-holding the drill will be readily attached to a work table or bench, or removed from the same, as circumstances may require. 65

Made with the breast of the bracket-frame *A*, at a distance below the plane of the lower end of the drill-spindle *B* of two inches, (more or less,) is a guiding or socket way, *h*, the bore of which socket is made with a uniform diameter and in a line parallel with the axial line of drill-spindle *B*. The said socket guides table *F* in its vertical movement by means of the guiding-pin *i*, made or attached to said table. 70

If preferred, the front side of socket *h* may be slotted, as shown at *o* in Figs. 1, 2, and 3, for receiving a bracing-piece, *j*, cast or made with both the table *F* and guiding-pin *i*. 75

If preferred, the guiding-socket may be dispensed with and a vertical rib cast with the breast of bracket *A* may be used for guiding the table in its vertical movements, and button-heads *m*, attached to said vertical guiding-rib, may be employed to operate against the marginal surfaces at the sides of slot *n*, made in an angle-piece, *p*, connected with table *F*, as shown in Figs. 4 and 5. Bracing-pieces made with angle-piece *p* and table *F* may be employed to stiffen said table with said slotted angle-piece. The said table, being thus held 80 and guided in its vertical movements by the guiding-pin *i* and socket *h*, may be readily ele- 90

vated by a hand of the operator for causing the drill in drill-spindle B to enter to a greater or less depth into a piece of metal supported by said table, or lowered for withdrawing the drill. The clamping-jaw *d* and clamping-screw *f* operate to hold the drill-spindle and the gears actuating the same firm and steady, so that the operator is not required to exert himself in the least to steady the drill, as is required with breast or bow drills heretofore employed by the class of workmen my improved drill is intended for.

If preferred, a drill-chuck may be attached to the drill-spindle for holding different size drills.

The manner of operation to be had with my improved drilling-machine is as follows: The drilling-machine is to be firmly secured to the work table or bench by the clamping jaw and screw, and the piece of metal to be pierced is to be laid on the movable table. With the point the said piece is to be pierced in a vertical line with the point of the drill. The operator will then with one hand gradually force the table, with the piece to be drilled, upward, while with his other hand he will impart motion to the drill by revolving gear-wheel C. When the drill has been made to enter the metal to the depth intended the operator will lower the table with his hand. In cases where the piece to be drilled is so large as not to be admitted on the table, the table may be readily removed by simply lifting it upward until the guiding-pin is free from the guiding-socket.

I am aware that bench drilling-machines provided with clamping-jaws and clamping-screws for attachment to a table or bench, and made with a bracket for supporting a drill-shaft vertically over a movable table operated by a lever, are old and well known. Such machines had the drill-shaft made with a spiral ribbed or screw form, and were operated by a reciprocating movement of the operator's hand, in which the downward movement of the hand forced a fixed pin to be moved downward through the entire length of the spiral channel of the drill-shaft and gave a rotary movement to the same, which was continued by means of a balance-wheel provided on the shaft, while the pin was carried upward for another downward movement of the same to continue the motion. Such machines I do not claim as being my invention, as they do not

operate by the same principles of mechanism or means, and are therefore not adapted for fine and accurate work, as required by jewelers, for the reason that the rotations of the drill in these older machines are not uniformly the same against the resistance attending drilling of metals, and the movement of one of the operator's hands in a reciprocating manner, alternately forcible and light, tends to prevent his having accurate and complete control over the required movements of his other hand and the work the drill is operating with, while another defect is that when the work is not fixed to the drill-table the operator is required to call in the service of another to operate the drill, while he directs and controls the movement of the lever of the table and holds the work being drilled. My invention is intended to provide a drilling-machine with which a single person may operate the drill and hold and control his work and direct the movements of the drill-table in an easy and convenient manner and by natural movements of his hands, so that the work will be accurately done, while the drill will be made to revolve uniformly the same with one hand and the work be held and directed in its movement toward the drill, whether faster or slower, by the other hand.

Having described my invention, what I desire to claim and secure by Letters Patent is—

1. In a bench drilling-machine, as my improvement, the work-supporting table unencumbered with mechanism for adjusting and holding the same at different elevations suited to the work to be drilled, but free to be moved up and down by the hand that clamps the work upon it, at the will of the operator.

2. In a bench drilling-machine, the combination, with bracket-frame A, provided with a clamping mechanism for its attachment to a bench, drill-spindle B, held from being moved vertically, and gear mechanism C and E and crank-handle D for rotating said drill-spindle, of the work-supporting table F, held in connection with said bracket-frame and unencumbered with adjusting and holding mechanism, but free to be moved up and down to different elevations by the hand that clamps the work upon the table, at the will of the workman.

WALTER S. BROWER.
